UNITED STATES PATENT OFFICE.

JOVID E. ROBERTS, JR., AND HENRY HARRISON SHEETS, OF WASHINGTON, DISTRICT OF COLUMBIA, ASSIGNORS TO AMERICAN FORMBLOCK SYSTEM COMPANY, OF WASHINGTON, DISTRICT OF COLUMBIA, A CORPORATION OF DELAWARE.

BUILDING CONSTRUCTION.

Application filed September 22, 1926. Serial No. 137,033.

This invention relates to building construction and has special reference to double walls formed of concrete blocks, the object being to produce a wall of novel construction which 5 may be hollow or solid, as preferred, and to which plaster or stucco may be easily applied and will be positively anchored.

The invention also has for an object the production of a block of novel form which 10 may be easily laid in courses to produce inner and outer walls without requiring a block in one wall to be set with special reference to a particular block in the other wall and with which re-enforcing rods may be easily 15 assembled in such a manner as to insure alignment of the blocks and their proper spacing in the two walls.

Other objects will appear in the course of the following description.

20 In the accompanying drawings:

Figure 1 is a perspective view of a portion of a wall embodying the invention;

Fig. 2 is a plan view of the same;

Fig. 3 is a perspective view of an outside 25 corner block;

Fig. 4 is a similar view of an inside corner block;

Fig. 5 is a similar view of an intermediate or side block.

30 Referring particularly to Fig. 5, there is shown a side block, consisting of a body 1, which is substantially rectangular and of dimensions conforming to standard practice, or to meet special requirements. On one side 35 face, the body is formed with vertical grooves or notches 2 having parallel walls set obliquely with respect to the face of the block so that the grooves or notches will not be merely surface channels but will constitute, in effect,

40 chambers within the body opening through the side thereof, and each having one overhanging wall. As a result of this formation, when the blocks are built into a wall and a trowel is run over the surface to apply stucco or plaster thereto, the stucco or plaster will be forced into the grooves or notches and thereby firmly anchored or keyed in place. On the opposite face of the blocks are formed 45 three vertical lugs or tongues 3 and 4, the lugs 4 at the ends of the blocks being each one-half the width of the central lug or tongue 3 whereby, when blocks are superposed in break-joint relation, the spaces 5 between the lugs on all the blocks will be brought into

vertical alignment. By this means an adequate and full bearing surface is provided for all blocks as they are laid. The opposed side edges or walls of the lugs are formed with vertical grooves 6 where they meet the main body of the block so that when a concrete or other plastic filler, as shown at 7 in Fig. 2, is poured into the space between the two walls, the filler will be firmly anchored to the blocks and a stable strong wall will result. In the top and bottom of all the lugs, 55 grooves 8, preferably semi-cylindrical, extend longitudinally of the block to receive re-enforcing rods, as at 9 in Fig. 1, and these grooves are all set at the same distance from faces of the lugs so that when the re-enforcing rods are placed in the grooves the blocks in a course will be aligned end to end and the blocks in superposed courses will be held also in proper vertical alignment, inasmuch as the rods will engage in the grooves in the meeting faces of the superimposed blocks, as 60 shown in Fig. 1.

50 In the top and bottom of each block, there are depressions or cups 10 to receive mortar which will form a key or dowel to bond the 65 blocks together.

Longitudinal grooves 11 are also formed in the top of the main body of the block to receive the ends of tie-rods 12 (see Fig. 1) which extend across the space between the 70 inner and outer walls and engage in like 75 grooves in the two walls to tie the walls together. Preferably, the tie-rods are disposed so that they will pass across the spaces 5 and will be relatively thin so that they will be 80 covered by the mortar between the courses of blocks.

85 In Fig. 3 there is shown an outside corner block 13 which has all the structural features of the side block shown in Fig. 5 and set forth in the foregoing description, except that at one end the lug 4 is omitted and a branch 14 is substituted therefor, said arm or branch extending laterally from the main body of the block. It will be understood, of course, that while the drawing shows the branch member as formed at a right angle to the main body it may be arranged at a greater or less angle to meet the conditions in any particular building operation. The branch 100 14 is provided at its end on its inner face with a lug 15 corresponding in all respects to the end lug 4, except that it is at an angle 105

to the central lug. The space 16 between the lug 15 and the central lug 3 follows the angle of the block and a plastic filler poured therein will, of course, be keyed to the two branches 5 of the block. The aligning and re-enforcing rod 9 may be bent, as at 17, if desired, to conform to the angle of the block and thereby aid in maintaining the angle in the wall.

In Fig. 5, an inner corner block is shown. 10 This block 18 differs from the outer corner block in having the recesses or grooves 2 in the sides of its inner angle while the anchoring lugs are formed on the sides of its outer angle. It will also be noted that an angular 15 lug 19 is provided at the outer corner of the block to project from both of the meeting outside faces of the block, and one of the grooves 8 in said lug opens through a side of the lug so that the end of the aligning and 20 re-enforcing rod may be anchored in the plastic filler, as indicated at 20.

In building a wall of these blocks, the blocks are laid in courses with mortar between the courses, the aligning and tie-rods 25 being placed in position as each course is laid, it being understood that the inner and outer walls are erected simultaneously. In laying the courses, the blocks are so placed that they will break joint and, to this end, 30 the corner blocks are reversed in the alternate courses, having their longer arms or main portions in one side of the wall in one course and in the other side of the wall in the next course. In this method of construction, so far as the individual blocks are concerned, the impractical features which have characterized many previously devised concrete blocks systems are eliminated, and each 35 wall is constructed independently of the other wall. There is no necessity for the blocks in one wall "mating" or having any definite position in reference to those in the other wall. The usual masonry methods and practice are all that is necessary to insure 40 a solid permanent construction.

After the walls have reached a sufficient height, the plastic filler 7 is poured, if a filler is to be used, and after the building of the wall is completed plaster 21 is applied 50 to the inner surface of the inner wall and stucco 22 to the outer surface of the outer wall. The stucco, however, may be omitted and the outer surface of the outer wall be furnished by the outer faces of the blocks 55 which may be given any desired finish.

A structure built with our blocks under our system, may be rapidly erected at a low cost, and attains maximum strength and durability. Such a structure becomes a homogeneous, monolithic mass as soon as the concrete filler has permanently set.

By providing both inside and outside corner blocks the wall corners are sharply defined and the proper relation of the inner and 60 outer walls is assured. The peculiar form of

the grooves in the outer faces of the blocks provides positive and highly efficient anchorage for the stucco or plaster and they are so disposed that proper anchoring of the stucco or plaster cannot be avoided. The form of the retention grooves or spaces in the opposed faces of the blocks produces a very substantial and firm binding between the blocks and the plastic filler. Because of the shapes of the inner and outer corner blocks 70 as well as because of the type of construction 75 a permanent, earthquake-proof structure is attained by this system.

The inner and outer walls may be placed any desired distance apart according to the thickness desired in the finished wall without affecting the manner in which the blocks are to be laid, and the distance apart of the two walls accurately maintained without additional structure by the use of the cross tie-rods 12, which always accurately maintain the proper distance of one wall from the other.

What we claim as new and desire to secure by Letters Patent of the United States is:

1. A wall structure composed of inner and outer walls of superimposed blocks, the blocks forming said walls having vertically extending lugs on their opposed faces with the side edges of the lugs in overhanging relation to the face of the blocks, and grooves across the ends of the lugs extending longitudinally of the blocks, aligning and reinforcing rods seated in said grooves and extending the full length of the wall structure, tie rods having their ends engaged in the tops of the blocks in corresponding courses in the inner and outer walls, and a plastic filling embedding the lugs, the tie-rods and the aligning and reinforcing rods, whereby all of the elements 95 of the structure are formed into a single wall unit.

2. A wall structure composed of inner and outer walls of superimposed blocks, the blocks forming said walls having vertically extending lugs on their opposed faces with the side edges of the lugs in overhanging relation to the face of the blocks, and grooves across the ends of the lugs extending longitudinally of the blocks, aligning and reinforcing rods seated in said grooves and extending the full length of the wall structure, tie rods having their ends engaged in the tops of the blocks in corresponding courses in the inner and outer walls, and a plastic filling embedding 100 the lugs, the tie rods and the aligning and reinforcing rods, whereby all of the elements 105 of the structure are formed into a single wall unit.

3. A wall structure composed of inner and outer walls of superimposed blocks, the blocks forming said walls having vertically extending lugs on their opposed faces with the side edges of the lugs in overhanging relation to the face of the blocks, and grooves across the ends of the lugs extending longitudinally of the blocks, aligning and reinforcing rods seated in said grooves and extending the full length of the wall structure, tie rods having their ends engaged in the tops of the blocks in corresponding courses in the inner and outer walls, and a plastic filling embedding 115 the lugs, the tie rods and the aligning and reinforcing rods, whereby all of the elements 120 of the structure are formed into a single wall unit, and all of the blocks having vertically extending grooves on the faces thereof opposite the lugs and disposed obliquely to the longitudinal axis of the blocks whereby a finishing surface may be bonded to the structural unit.

3. An angular shaped wall structure com- 130

posed of inner and outer walls of superimposed blocks and having a plastic filling between said inner and outer walls, certain of said blocks being in angular formation to 5 form the inner and outer corners of said structure, all of said blocks being provided with a plurality of vertically extending lugs having edge portions in overhanging relation to the sides of the blocks, the lugs on the 10 inner wall of angular blocks being disposed adjacent to the plastic filling, the lugs on the outer wall of outer blocks being disposed adjacent the plastic filling and in opposed re-

lation to the blocks on said inner wall and all of said blocks having vertically extending 15 grooves on the face thereof opposite the lugs, said grooves being disposed obliquely relative to the longitudinal axis of said blocks and said structure having a finishing surface of both walls of blocks, and bonded thereto 20 in said grooves.

In testimony whereof we have hereunto affixed our signatures.

OVID E. ROBERTS, JR.
